CARBURETOR CONTROL LINKAGE

Harold Nutt, Chicago, Ill., assignor to Borg-Warner Corporation, Chicago, Ill., a corporation of Illinois

Application February 1, 1945, Serial No. 575,642

8 Claims. (Cl. 74—516)

1

The present invention relates to a control linkage for carburetors. The arrangement is especially adapted for use to control the speed of a centrifugal clutch when the latter is a part of the power unit in a motor vehicle.

With centrifugal clutches of this character the dictated or desirable engine speed for initially engaging the clutch is approximately 800 R. P. M. and a complete clutch engagement may be attained with engine speeds between 1,200 R. P. M. and 2,000 R. P. M. Usually, a small travel of the throttle pedal, for example $\frac{1}{2}$ inch, will speed up the engine from the customary idling speed of 400 R. P. M. to a speed for the full clutch engagement. This, however, renders it difficult to park a motor vehicle equipped with a centrifugal clutch. By the use of the present device, the same $\frac{1}{2}$ inch travel of the throttle pedal will increase the engine speed only slightly above the initial engaging speed for the centrifugal clutch. This results in only enough developed torque to slowly move the car at a creeping speed for parking, and at the same time it gives the operator a nicety of control that is comparable with manual clutch operation. Although it is not required, the present control arrangement may be operated in two steps or stages. This will permit the operator to depress the accelerator pedal an initial distance that is indicated by the travel of a cam with considerably less effort than is thereafter required for the additional and full opening of the throttle. Thus the operator will be able to feel the location during the pedal movement at which the initial or cam action ceases, and since this is the point where the engine should run for parking the car, no accurate control of the accelerator pedal is required.

It is contemplated that the present assembly be mounted upon the carburetor, preferably carried by the spindle or shaft that moves the butterfly throttle valve. The arrangement is such that the valve is moved slowly to the open position that is desirable for the initial engagement of the centrifugal clutch during the operation of parking the car, and from that point on all the parts of the linkage are adapted to move as a unit for rapidly opening the throttle for ordinary driving purposes.

It is therefore the principal object of this invention to simplify the construction of a carburetor control that is adapted for use with a centrifugally acting clutch, and to improve the operation of such carburetor control.

It is also an object of this invention to pro-

2

vide a control device wherein there is initially a very small movement of the throttle butterfly in the carburetor for a considerable travel of the accelerator pedal. This is highly desirable with a centrifugal clutch to permit accurate control of engine speed at relatively low R. P. M. when parking a car in close quarters.

Another object of this invention is to provide a carburetor control that is adapted to readily affect the initial engagement of a centrifugal clutch in a manner so that the driver is easily able to operate the vehicle at very low speeds as for example when moving the car a few inches at a time.

Another object of this invention is to provide a control linkage for a carburetor such as contemplated herein which preferably comprises a unitary assembly, the parts of which are constructed and arranged for ready mounting upon a portion of a carburetor, preferably the butterfly valve spindle, whereby there is provided an accurate control for light torque clutch engagement when parking a motor vehicle equipped with a centrifugal clutch.

Numerous additional objects, aims and advantages of the invention contemplated herein will be apparent to persons skilled in the art after the construction and operation of the carburetor control linkage is understood from the within description. It is preferred to accomplish these objects and to practice the invention in substantially the manner hereinafter fully described and as more particularly pointed out in the appended claims. Reference is now made to the accompanying drawings that are a part of this specification, in which:

Fig. 1 is a side elevation of a motor vehicle power plant showing the carburetor control linkage installed thereon;

Fig. 2 is an enlarged side elevation of the control assembly, showing in dotted lines the first stage of operation;

Fig. 3 is a view similar to Fig. 2 showing the stage of operation for full clutch engagement with the throttle opened a substantial distance; and

Fig. 4 is a sectional view taken along the plane of line 4—4 on Fig. 2.

The drawings are to be understood as being more or less of a schematic character for the purpose of disclosing a typical or preferred embodiment of the improvements contemplated herein. In these drawings like reference characters identify the same parts in the different views.

Referring to Fig. 1, the power plant embodies engine 5, clutch assembly 6, and transmission 7 in tandem arrangement. The clutch assembly comprises flywheel 8, clutch disk 9, and pressure plate 10, the latter normally held out of engagement with disk 9 by reaction springs (not shown) and adapted to be engaged with said disk by centrifugal action of pivoted weights 11, there being a normal driving connection between the pressure plate and the fly-wheel. The weights are fulcrumed on the usual reaction annulus. When the throttle pedal 12 is depressed by the operator the engine will speed up in the usual manner and, as the engine speed increases, the weights 11 swing radially outward to move the pressure plate toward the fly-wheel 8 thereby to engage the clutch.

Throttle pedal 12 is connected by rod 13 to an end of a first-class lever 14 which at its other end pivotally carries the adjacent end of a reciprocable accelerator rod 15 for the carburetor assembly 16 on the engine. A collar 17 pinned to rod 15 is engaged by one end of a helical spring 18 that is suitably anchored at its other end to a boss 19 on the engine, thereby to urge the rod in one direction of its reciprocable movement. The carburetor includes the body or fuel bowl 20 and the throat 21, that is demountably connected to the engine intake manifold 22. Throat 21 has therein the main fuel passageway 23 which communicates with the inlet stub 24 of manifold 22. The throttle or butterfly valve 25 in passageway 23 is carried on a spindle 26 that is elongated at one end to project out of its bearing as seen in Fig. 4.

Referring particularly to Figs. 2 and 4, the throttle lever 27 comprises an arm having a split boss 28 at one end that is clamped to the extended portion of spindle 26 by a cap screw 29, and a helical spring 27a, hooked to the swinging or free end of throttle lever 27, urges said lever to one of the limits of its swinging movement, or to the right as seen in Fig. 2. The other end of spring 27a is connected to a fixed lug 26a on the engine. Beside the throttle lever 27 there is bifurcated lever 30 having a generally U-shape and unsecured to spindle 26 so that it is free to swing on said spindle 26 upon which it is retained by a washer 31 and cotter pin 32. There is an extension 33 on the idle lever 30, projecting below its fulcrum, and having a threaded boss to receive adjusting screw 34 that is maintained in position by lock-nut 35. As seen, the adjusting screw projects out of the idle lever boss to engage with a stop 36.

The throttle lever 27 is not directly connected to the accelerator rod 15. A lateral pin 37 on throttle lever 27 pivotally mounts a swinging cam device or arm 38 which has its outer end engaged with a pin 39 on an internally threaded swivel block 40 adjustably screwed upon the threaded end region 17a of accelerator rod 15. Cam arm 38 has an eccentric boss 41 at its fulcrum, said boss arranged to engage a suitably shaped edge 42 on one of the members of the U-shaped idle lever 30 against which this cam boss bears by reason of the urge of spring 27a and spring 18.

When accelerator rod 15 is moved to the left (Fig. 2) by a depression of the throttle pedal 12, the cam arm 38 will swing counterclockwise on its pivot 37 while the cam boss 41 engages the edge 42 of the idle lever 30. Since the idle lever 30 is arrested at this time from moving clockwise by reason of the stop 36, the camming action of

5 arm 38 will swing the throttle lever counterclockwise or to the left as shown by dotted lines on Fig. 2 while the U-shaped idle lever 30 remains stationary. The effect of this camming action is that the spindle 26 is slowly rotated to open the butterfly valve 25 the proper distance for running the engine at the desired slow speed to accomplish the initial coupling of the centrifugal clutch. As a result the engine will drive the vehicle through the clutch and transmission, at a creeping speed which is slow enough to permit the operator to park the car.

As will be seen, the throttle lever 27 is alongside this idle lever (Fig. 4) and the cam arm 38, or at least its cam boss 41, is located between the members of the U-shaped idle lever 30. In normal or idling position, the outer end portion of cam arm 38 is engaged with a stop ear 43 at the end of an adjacent member of U-shaped idle lever 30, and at the end of the initial movement of the cam arm 38 a projection 44 of this cam arm will engage a stop 45 at the outer end of the second member of idle lever 30. These stops 43 and 45 limit the free swing of the cam arm 38 and they also predetermine the amount of opening effected by the butterfly valve 25 to initially couple the clutch for creeping movement of the vehicle. Further depression of the throttle pedal 12 will shift the accelerator rod 15 20 farther to the left, which, after cam arm 38 has engaged stop 45, will move the whole assembly (including the idle lever 30 and throttle lever 27) to the left for a full open position of butterfly valve 25. This will accelerate the engine speed 25 for a complete coupling of the clutch.

30 It will be seen, when the operator depresses throttle pedal 12 a distance for the cam arm 38 to engage stop 45, such engagement will be sensed by him because thereafter further depression of the pedal will require more effort to operate the assembly as a unit to move such unit to a position for driving the vehicle at a desired speed.

40 While this invention has been described in detail in its present preferred form or embodiment, it will be apparent to persons skilled in the art, after understanding the improvements, that various changes and modifications may be made therein without departing from the spirit or scope thereof. It is aimed in the appended claims 50 to cover all such changes and modifications.

I claim:

1. In combination with a rockable spindle for a carburetor throttle valve and the like, a rocker arm secured to said spindle for oscillating the same; a manually reciprocable actuator rod; and control means operatively connecting said arm and actuator rod for effecting multiple-stage movement of said spindle, said control means comprising an idle lever swingingly mounted on said spindle; means arresting movement of said idle lever in one direction; and a cam device rotatably mounted on said rocker arm, said cam device having operative connection with said rod and being adapted to act on said idle lever when the latter is in said arrested position for effecting movement of said arm independently of said idle lever to rock said spindle through a first stage of its movement; and continued movement of said cam device being effective to move said idle lever away from its arresting means and rock said spindle through another stage of movement.

2. In combination with a rockable spindle for a carburetor throttle valve and the like, a rocker arm secured to said spindle for oscillating the same; a manually reciprocable actuator rod; and

control means operatively connecting said arm and actuator rod for effecting multiple-stage movement of said spindle, said control means comprising an idle lever swingingly mounted on said spindle, said idle lever having spaced members; means arresting movement of said idle lever in one direction; and a cam device operatively connected to and rotated by said rod, said cam device fulcrumed on said rocker arm in engagement with a member of said idle lever and acting thereon when the idle lever is arrested for effecting movement of said rocker arm independently of said idle lever to rock said spindle through a primary stage of its movement, and the continued movement of said cam device being effective to engage it with another member of said idle lever for effecting bodily movement of said idle lever and the simultaneous movement of said rocker arm to rock said spindle through another stage of movement.

3. In combination with a rockable spindle for a carburetor throttle valve and the like, a control assembly for effecting the rocking of said spindle in two stages, said assembly comprising a rocker arm secured to said spindle; a manually shiftable rod; a cam arm pivoted for limited swinging movement on said rocker arm; means operatively connecting said rod and said cam arm; an idle lever swingingly mounted on said spindle, said idle lever having spaced members positioned upon opposite sides of said cam arm whereby the aforesaid limited movement of the cam arm is effected by engagement of said cam arm with one and then the other of the respective idle lever members; a stop arresting movement of said idle lever in one direction; said cam device during its limited movement being adapted to act upon a member of said idle lever when the latter is arrested for effecting a first stage movement of said rocker arm independently of said idle lever, and a continued movement of said cam device acting to move said idle lever away from said arresting means and simultaneously therewith to effect a second stage movement of said rocker arm to further rock said spindle.

4. A control assembly for an oscillatable spindle comprising a rocker arm secured to the spindle; a member swingingly mounted on the spindle independent of said arm; a fixed abutment effective to arrest movement of said swinging member in one direction; a cam device rotatable on said rocker arm, said cam device being effective to act on said swinging member while in arrested position thereby to actuate said rocker arm and partially rock said spindle; and a manually operable rod connected to said cam device for rotating the latter.

5. A control comprising a rotatable spindle; a rocker arm secured to said spindle; an oscillatory idle lever swingingly carried by said

5

spindle; a stop for arresting movement of said idle lever in one direction; an actuator device pivoted on said rocker arm and having operative connection with a manually reciprocated rod, whereby said actuator device is shifted on said rocker arm; and a cam operated by said actuator device, said cam being engaged with said idle lever and being effective when said lever is arrested to move said rocker arm a predetermined distance independent of said idle lever.

6. A control as defined in claim 5 wherein the idle lever has a stop for limiting the predetermined independent movement of the rocker arm.

7. A control assembly for a rock spindle, comprising an arm secured to said spindle, said arm being movable to rock said spindle; an oscillatory idle lever movable on said spindle, said lever having a predetermined limit of movement in one direction; a cam device fulcrumed on said arm in engagement with said idle lever, said cam device being adapted for movement independent of said arm also with said arm, the said independent movement of said cam device being ineffective to move said idle lever from its arrested position but is effective to initially move said arm to slowly rock said spindle a predetermined distance; and a reciprocable manually operable rod connected to and actuating said cam device.

8. A control assembly for a rock spindle, comprising an oscillatory arm secured to said spindle for rocking the same; an oscillatory U-shaped idle lever movable on said spindle, said lever having arrested movement in one direction; a cam device swingingly carried by said arm for bodily movement therewith, said cam device being adapted during its swinging movement to successively engage with one member and then the other member of said U-shaped idle lever; and a longitudinally reciprocable manually operable rod connected to said cam device independent of said arm; said assembly being so constructed and arranged that initial movement of said cam device effects a relatively slow swing of said arm while said lever is arrested whereby to slowly rock said spindle a portion of its rotation, and further movement of said cam device effects a relatively rapid rocking of said spindle by a simultaneous movement of said arm and lever to complete the rotative movement of said spindle.
